CLAIM

The ornamental design for a protective enclosure for an electronic device, as shown and described.

DESCRIPTION

FIG. 1 is a front isometric view of a protective enclosure for an electronic device showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dot-dash-dot broken lines represent a boundary of the claimed design that forms no part of the claim. The dash-dash-dot broken lines depict portions of the article that form no part of the claim.
